UNITED STATES PATENT OFFICE.

JAMES L. BOYER, OF JOHNSTOWN, PENNSYLVANIA.

AUTOMATIC TRAIN-STOPPING APPARATUS.

1,102,132.

Specification of Letters Patent. Patented June 30, 1914.

Application filed January 14, 1914. Serial No. 812,123.

To all whom it may concern:

Be it known that I, JAMES L. BOYER, a citizen of the United States, residing at Johnstown, in the county of Cambria and State of Pennsylvania, have invented new and useful Improvements in Automatic Train-Stopping Apparatus, of which the following is a specification:

This invention relates to improvements in automatic train stopping apparatus and has particular application to an electrically controlled apparatus of this type.

In carrying out the present invention, it is my purpose to provide an apparatus of the class described which will be found especially useful in conjunction with the block signal system and whereby the propelling power of the motor car will be cut off and the brakes applied automatically in the event of such car passing a danger signal and wherein the car carried mechanism will be under the control of the signal system of the railway.

It is also my purpose to provide an automatic train stopping apparatus which will operate efficiently and effectively under all weather conditions and which may be installed and maintained at a minimum expense.

With the above and other objects in view, the invention consists in the construction, combination and arrangement of parts hereinafter set forth and falling within the scope of the claims.

In the accompanying drawings; Figure 1 is a diagrammatic view of a car carried mechanism. Fig. 2 is a diagrammatic view of the track circuits. Fig. 3 is a top plan view of a portion of a car carried mechanism. Fig. 4 is an enlarged side elevation of the same. Fig. 5 is a sectional view on the line 5—5 of Fig. 3. Fig. 6 is a transverse sectional view through the trackway and the motor car thereon. Fig. 7 is a view in side elevation of a car controlled switch, parts being shown in section. Fig. 8 is a view in elevation of the controlling relay of the car carried stopping mechanism. Fig. 9 is a view in elevation of a controlling relay for an electric locomotive.

Referring now to the drawing in detail, 1, 1 designate parallel lines of rails forming the trackway. In the present instance, the lines of rails of the trackway are divided into sections or blocks of any suitable length

by means of insulation 2. Located at the entrance to each block is a semaphore 3 embodying a signal blade 4 working in the upper quadrant and indicating "danger" when horizontal and "clear" when vertical, and a motor 5 connected up with the blade 4 and holding the latter in the clear position. As is well known, the motor 5 is connected in a normally closed electric circuit 6 including a suitable source of electrical energy as a battery 7 and under the control of the armature of a normally energized track relay 8, the terminals of the track relay being connected to the opposite rails of the respective block and receiving current from a battery 9 having the poles thereof connected with the rails of the block.

Located in advance of the entrance to each block are contact rails 10, 10 disposed between the lines of rails of the trackway and leading from one end of one of said rails is a conductor 11 connected with one side of a battery 12, while from the remaining contact rail leads a conductor 13 connected to the pivot point of an armature 14 under the influence of the track relay 8 of the respective block and normally held in open position. In the path of movement of the armature 14 is a contact 15 connected with the other side of the battery 12 by way of a wire 16. By means of this construction, it will be seen that as long as the track relay 8 is energized, the motor circuit 6 will be closed and the partial circuit composed of the battery 12, wire 16, conductors 13, and contact rails 10, 10 open. On the other hand, when a train enters the block, the battery 9 is short circuited and the relay 8 de-energized whereby the relay armature and the armature 14 gravitate to lower position thereby opening the motor circuit 6 and closing the partial circuit including the contact rails 10, 10 open. Upon the breaking of the motor circuit, the signal blade gravitates to danger position.

Depending from each motor car or locomotive adjacent to the forward end thereof are brackets 17, 17 spaced apart transversely of the car and each provided with vertically alining bearings 18, 18. Within the vertically alining bearings 18, 18 of each bracket is slidably mounted a rod 19 having a collar 20 surrounding the same and fast thereto adjacent to the lower bearing, while enclosing the rod is a coiled expansion spring 21.

- having one end bearing against the collar 20 and the opposite end in engagement with the upper bearing 18, such spring acting to maintain the rod against upward movement.
- 5 Suitably secured to the lower ends of the rods 19, 19 are contact shoes 22, 22 adapted to ride upon the contact rails 10, 10 in the travel of the car, along the trackway and in order to insure good contact between the 10 contact rails and the shoes, the opposite ends of the rails are inclined downwardly so that frictional contact between the shoes and the rails will be gradually increased under the action of the springs 21.
- 15 Mounted upon the motor car or locomotive is a controlling relay 23 comprising, in the present instance, a casing 24, an electromagnet 25 secured to the bottom wall of the casing and an armature 26 pivotally mounted 20 upon a bracket within the casing 24 and having one end thereof disposed within the influence of the pole of the magnet 25 and the opposite end downturned to form a detent 27. The terminals of the winding of 25 the magnet 25 are connected with the upper end of the rods 19 by way of wires 28 so that should the car attempt to enter a block against the set danger signal, the winding of the magnet 25 will become energized owing 30 to the shoes 22, 22 riding into engagement with the contact rails 10, 10 in circuit with the battery 12, current flowing from one side of the battery through the wire 11, the respective contact rail 10, the shoe 22, the respective wire 28, the winding of the magnet 25, the remaining wire 28, shoe 22, contact rail 10, the conductor 13, armature 14, contact 15 and back to the other side of the battery by way of the wire 16.
- 40 An electric motor 29 is mounted upon the boiler of the engine in advance of the steam dome and is connected in an electric circuit 30 including a suitable source of energy with a battery 31 and a double pole switch 32.
- 45 The switch 32 is disposed within the casing 23 of the controlling relay and the blades thereof are normally held open by the dog 27 on the armature 26, while a coiled contractile spring 33 has one end connected to 50 such blades and the opposite end fastened to the adjacent end wall of the casing and acts to swing the blade to closed position succeeding the release of the same by the dog 27 incident to the swinging of the armature upon the energization of the magnet 25. In the present instance, a butterfly valve 34 is located in the steam main between the throttle valve and the drive cylinders of the engine and the stem of such valve is connected 55 with a vertical shaft 35 extending through the top of the boiler and terminating adjacent to one end of the armature shaft of the motor 29. Loosely surrounding the vertical shaft 35 is a bevel gear 36 and 60 meshing with such gear is a pinion 37 keyed

to the adjacent end of the armature shaft of the motor 29, while fixed to the under surface of the bevel gear 36 is a disk 38 having a depression 39 formed in the periphery thereof. This depression 39 has the 70 lower wall thereof inclined and gradually merging into the periphery of the disk 38. Fixed to the shaft 35 adjacent to the upper end thereof is a disk 40 formed with an arcuate shaped slot 41 adjacent to the periphery thereof and within such slot works a pin 42 carried by the bevel gear 36 and projecting upwardly from the upper surface thereof. In this embodiment of my invention, the disk 40 is provided with a 80 crank pin 43 connected through the medium of a link 44 with the handle 45 of the engineer's brake valve 46 so that when the disk 40 revolves under the action of the shaft 35, the engineer's brake valve will be manipulated to bleed the brake pipe or train line air pipe.

Adjacent to the shaft 35 is a latching device comprising a casing 47 in which is slidably mounted a latching pin 48 having one end normally lying within a recess 49 formed in the periphery of the disk 40, a coiled expansion spring 50 encircling the latching pin 48 within the casing 47 and having one end abutting a collar 51 on the latching pin and the opposite end in engagement with the opposite end wall of the casing. Depending from the latching pin 48 is an arm 53 carrying a right angularly extending pin 54 disposed within the recess 39 10 in the periphery of the disk 38.

In practice, when the motor 39 is energized as previously described, owing to the train or car passing a danger signal, the bevel pinion 37 meshing with the gear 36 revolves the latter and in the initial rotation of the disk 38 under the action of the bevel gear 36 the inclined wall of the recess 39 actuates the pin 54 with the effect to retract the latching pin 48 from the recess or notch 49 11 in the disk 40. Immediately succeeding the release of the disk 40, the pin 42 engages the end wall of the slot 41 and so revolves the disk 40 thereby rotating the shaft 35 to close the butterfly valve 34 and cut off the flow of steam from the boiler to the drive cylinders of the locomotive. In the rotation of the disk 40, the engineer's brake valve 46 is manipulated to bleed the brake pipe and thereby effect an application of the brakes to the wheels.

In the present instance, normally closed spring switches 55 are connected in the conductors 11 and 13 and connected to such switches is an actuating bar 56 arranged upon the outer side of one line of rails 1 immediately beyond the entrance to the respective block. This bar 56 is normally held in elevated position above the tread of the adjacent line of rails by means of coiled 12 13

expansion springs 57 disposed within suitable casings, such bar being of a length equal to the distance between the trucks on the cars. By means of this construction, it will be seen that after the motor car at the head of a train has entered the block and set the danger signal against a following train or car, the flanges of the wheels of the first train will ride into engagement with the actuating bar 56 and so actuate the switches 55 to open position thereby breaking the electrical continuity of the conductors 11 and 13 so that the car carried stopping mechanism on a pusher engine, that is, to say, an engine coupled to the rear of the train, will remain inactive when passing the danger signal.

In Fig. 9 of the drawings, I have illustrated a form of relay for controlling the motor circuit of the driving motors of an electric motor car, such relay comprising a pair of magnets 58, 58 spaced apart and connected in series with each other and the shoes depending from the car, and an armature 59 disposed within the influence of the poles of the magnets and connected with a horizontal rod 60 extending between the magnets 58, 58 and having one end thereof provided with a contact 61 normally engaged by a contact 62 on one end of an arm 63 pivoted as at 64. Encircling the rod 60 is a coiled expansion spring 65 acting to hold the contact 61 normally in engagement with the contact 62. The main feed wire 35 of the motor circuit of the car is broken and one of the terminals at the break therein connected with the pivots 64 of the arm 63 and the other terminal connected with the contact 61 on the rod 60. Thus, when the magnets 58 are energized the armature 59 is actuated to disengage the contact 61 from the contact 62 thereby permitting the arm 63 to gravitate to lowered position so that the motor circuit is broken.

While I have herein shown and described one preferred form of my invention by way of illustration, I wish it to be understood that I do not limit or confine myself to the precise details of construction herein described and delineated, as modification and variation may be made within the scope of

the claims without departing from the spirit of the invention.

I claim:

1. In train stopping apparatus, car carried mechanism comprising a motor, means for cutting off the propelling power of the car, a shaft connected to said means, a disk fixed to said shaft, a gear wheel loosely surrounding said shaft, driving connections between said gear wheel and motor, motor controlled means for effecting a rigid connection between said gear wheel and disk whereby said shaft will be rotated in the operation of the motor, a latching device holding said disk normally against movement, and means for releasing said latching device.

2. In train stopping apparatus, car carried mechanism comprising a motor, means for cutting off the propelling power of the car, a shaft connected to said means, a disk fixed to said shaft, a gear wheel loosely surrounding said shaft, driving connections between said gear wheel and motor, motor controlled means for effecting a rigid connection between said gear wheel and disk whereby said shaft will be rotated in the operation of the motor, a latching device holding said disk normally against movement, and motor controlled means for releasing said latching device.

3. In train stopping apparatus, car carried mechanism comprising a motor, means for cutting off the propelling power of the car, a shaft connected to said means, a disk fixed on said shaft, a gear loosely surrounding said shaft, driving connections between said gear and motor, means for operating said motor, means for establishing a rigid connection between said gear and disk succeeding the initial operation of the motor, a latching device holding said disk normally against movement, and means operable from said motor in the initial operation thereof to release said latching device.

In testimony whereof I affix my signature in presence of two witnesses.

JAMES L. BOYER.
